UNITED STATES PATENT OFFICE

2,439,675

LOOSE-LEAF BINDER

Samuel Segal, New York, N. Y., assignor to Wilson-Jones Company, Chicago, Ill., a corporation of Massachusetts

Application August 21, 1944, Serial No. 550,335

2 Claims. (Cl. 129—24)

1

This invention relates to a loose leaf binder of the type wherein a plurality of sectional rings are adapted to retain a plurality of apertured sheets. It refers particularly to a simple and efficient means for opening, closing and interlocking the sheet retaining rings.

It is an object of this invention to provide a loose leaf ring binder with a single booster adapted to open, close and interlock the rings. Other objects of this invention will become apparent upon reading the following description, taken in conjunction with the accompanying drawings, in which:

Figure 1 is a fragmentary perspective view of one embodiment of a loose leaf binder embodying my invention;

Figure 2 is a bottom plan view of the sheet retaining mechanism of Figure 1;

Figure 3 is a longitudinal sectional view taken along the line III—III of Figure 1;

Figure 4 is a view similar to Figure 3 showing the booster in the position it occupies when the sheet retaining rings are open;

Figure 5 is a cross-sectional view taken along the line V—V of Figure 3;

Figure 6 is a cross-sectional view taken along the line VI—VI of Figure 4;

Figure 7 is a view similar to Figure 3 showing a modified form of booster;

Figure 8 is a cross-sectional view taken along the line VIII—VIII of Figure 7;

Figure 9 is a detail perspective view of the booster shown in Figures 7 and 8;

Figure 10 is a perspective view showing the sheet retaining metal secured to the inside of a wallet;

Figure 11 is a view similar to Figure 3 showing another modified embodiment of the booster mechanism, and

Figure 12 is a cross-sectional view taken along the line XII—XII of Figure 11.

In the drawings the reference numeral 2 indicates a back member having a pair of cover members 3 hinged thereto in any suitable manner. The sheet retaining mechanism 4, which constitutes the subject matter of my invention, is secured to the back member by means of a plurality of rivets or eyelets 5. This sheet retaining mechanism may be of a size used in student note books, or, as indicated in Figure 10 of the drawings, may be made in miniature so that it may be secured to the inner fold of a wallet 6 or similar article.

In each embodiment disclosed the sheet retaining mechanism comprises a cover plate 7, which

is provided with a plurality of pairs of transversely aligned notches 8. A pair of rockable frame members 9 is positioned in the cover member 7. The rockable frame members 9 are each provided with a ring section 10 at each end. The ring section 10 on one of the rockable frame members mates with the ring section of the other rockable frame member so that the sections may be closed to form a pair of sheet retaining rings. The ring sections 10 project through the notches 8. The rockable frame members 9 are provided with toggle joints 11 to facilitate the opening and closing movement of the ring sections.

In the embodiment illustrated in Figures 1 to 15 of the drawings, the booster 12 comprises a flat strip of metal having one end 13 projecting through one end of the cover plate and bent upwardly to provide a finger piece to facilitate manipulation of the booster. The strip 12 is provided with a longitudinal slot 14 to permit passage of the rivet 5 and to permit longitudinal movement of the booster without interference from the rivet. The strip 12 is split longitudinally from its free end to provide a finger 15 positioned between the toggle connection 11 and the cover plate, and two fingers 16 which fit between the bottom surface of the ring sections 10 and the back member 2. The fingers 15 and 16 are curved as indicated in Figures 3 and 4. When the booster mechanism is in the position indicated in Figure 3, the finger 15 presses down against the toggle joint 11 so as to interlock the rings, and prevents opening of the rings by preventing upward movement of the toggle joints. As the finger piece 13 is pulled outwardly of the cover plate 7 the upward sweep of the finger 15 releases the interlocking pressure on the toggle joint 11 and the upwardly curved portion of the fingers 16 lift the portion of the ring sections 10 adjacent the toggle connection, as indicated at Figure 6, so as to open the ring sections. The slot 14 is of such length that, although it permits the booster to be moved longitudinally far enough to open or close the ring sections, it will engage the rivet or eyelet 5 at either end of its movement so as to prevent disengagement of the fingers 15 and 16 from the toggle joint 11.

The embodiment illustrated in Figures 7, 8 and 9 is similar to that previously described, except that the central finger 15' is stamped out of the body portion of the flat strip 12'. In this embodiment the space from which the finger 15' is bent provides sufficient clearance for the rivet 5. The rivet 5 engages the ends of this space, as in the embodiment previously described, to

prevent disengagement of the fingers 15' and 16' from the toggle connection. The fingers 16' are extensions projecting from the outer end of the strip 12'.

In the embodiment illustrated in Figures 11 and 12 of the drawings, the flat strip 12" does not project through the end of the cover plate but is provided with a transverse slot 17 through which a separate finger piece 18 is projected. The cover plate 7' is provided with a transverse slot 19 to permit the finger piece 18 to project therethrough. The finger piece 18 is provided with a foot portion 20 wide enough to prevent the finger piece from being removed through the slots 17 and 19. The sheet retaining mechanism is riveted to the back member 2 after the finger piece 18 has been projected through the slots 17 and 19.

Although I have described several embodiments of my invention in detail, it will be understood that the description thereof is intended to be illustrative, rather than restrictive, as many details may be modified or changed without departing from the spirit or scope of my invention. Accordingly, I do not intend to be bound to the exact construction described, except as limited by the appended claims.

I claim:

1. In a loose leaf binder, a cover member, a pair of rockable frame members positioned in said cover member, said rockable frame members having a toggle connection at each end, a slideable member having curved fingers engaging said frame members, said cover member and said slideable member each being provided with a transverse slot, and a lever passing through said slots, whereby said slideable member may

be moved longitudinally relative to said cover member, said curved fingers moving said rockable frame members vertically at said toggle connections when said slideable member is moved longitudinally relative to said cover member.

2. In a loose leaf binder, a pair of rockable frame members having a toggle connection at each end, said frame members terminating in ring sections, and a slideable member having one finger engaging both said frame members on one surface of one of said toggle connections and a pair of fingers, each engaging the opposite surface of one of said ring sections adjacent said toggle connection, said first mentioned finger being shaped to move said ring sections to closed position when said slideable member is slid towards said frame members and to hold said ring sections interlocked when said slideable member is in its innermost position, and said second mentioned fingers being shaped to open said ring sections when said slideable member is moved longitudinally away from said frame members.

SAMUEL SEGAL.
